UNITED STATES PATENT OFFICE.

ROBERT JOHNSON, OF FLORESVILLE, TEXAS, ASSIGNOR OF ONE-HALF TO I. YAHR, OF FLORESVILLE, TEXAS.

COMBINED RAIL-ANCHOR AND TIE-PLATE.

1,329,664.

Specification of Letters Patent.

Patented Feb. 3, 1920.

Application filed January 24, 1919. Serial No. 272,882.

To all whom it may concern:

Be it known that I, ROBERT JOHNSON, a citizen of the United States, residing at Floresville, in the county of Wilson and 5 State of Texas, have invented certain new and useful Improvements in Combined Rail-Anchors and Tie-Plates, of which the following is a specification.

This invention relates to new and useful 10 improvements in a combined rail anchor and tie plate.

The object of the invention is to provide a tie plate of the character described, whereby railway rails may be secured to the 15 underlying ties, and which will prevent the rails from cutting into the ties, and also which will secure said rails against overturning or spreading.

A further feature of the invention re- 20 sides in the provision of a rail anchor in combination with the tie plate, which will lock the rails against "creeping" on the ties.

With the above and other objects, in 25 view, the invention has particular relation to certain novel features of construction, operation and arrangement of parts, an example of which is given in this specification and illustrated in the accompanying drawings, wherein:

30 Fig. 1, shows a plan view of the device.

Fig. 2, shows a transverse sectional view, taken on the line 2—2 of Fig. 1, and

Fig. 3, shows an enlarged fragmentary 35 sectional view taken on the line 3—3 of Fig. 2.

Referring now more particularly to the drawings wherein like numerals of reference designate similar parts in each of the figures, the numeral 1, refers to a railway 40 rail, of the usual design, and the numeral 2 designates the tie plate which is a rectangular metallic plate designed to rest upon the ties underneath the rail. This plate has the usual openings 3, provided to receive the 45 spikes 4, which are driven through said openings and into the ties underneath, said spikes having the enlarged heads 5, which engage over the corresponding rail flanges 6, to secure the plate and rail upon the ties.

50 The inner side of the plate has an upstanding catch 7 cast integral with the plate which engages over the inner rail flanges to secure the rail against overturning outwardly and the plate is made tapering, being somewhat thicker on the outside than

on the inside, which causes the rails to converge slightly inwardly, thus preventing the track from spreading, particularly in going around curves. Ribs 8 are formed integrally with the plate, outside of each of the 55 spikes 4, the inner ends of said ribs abutting against the spikes and reinforcing the same and the plate is thickened on each side of the outer spikes and on the outer side of each of the inside spikes, thus strengthening 60 said plate at the points of the greatest stress. Secured to the outer edge of the plate between the corresponding ribs 8 is a detachable anchor 9, which is secured to the plate by means of bolts 10 and 11, said bolts passing 65 upwardly through the plate and through said anchor, and having their heads countersunk in the bottom of the plate. The upper ends of these bolts are threaded and receive the nuts 12, 12, to secure them in 70 position and to secure the anchor fast to the plate. The inner end of the anchor is spaced from the plate and located between it and the plate, is the cam 13, through 75 which the bolt 11 passes. The periphery of 80 this cam is serrated, and attached to its inner edge is the pull spring 14, whose other end is secured to the anchor 9. The pull of this spring holds the cam locked against the outer edge of the adjacent flange 6. From 85 an inspection of Figs. 1 and 3, it is obvious that the cam 13 may be caused to engage against the adjacent flange to prevent the rail from "creeping" in either direction, and thereby used particularly in the construction of curves. In building a track, some of the cams 13 may be positioned so as to prevent the rail from "creeping" in one 90 direction, and the others may be positioned so as to lock the rail from "creeping" in the opposite direction. As shown in Fig. 1, the cam is in position to lock the rail against "creeping" in the direction indicated by the arrow. The different positions of the cam are shown in full and also in dotted lines 95 in Fig. 3.

In case it is desired to remove the anchor and the "anti-creeping" device, it is obvious that the same may be done by loosening the nuts 12, and removing the bolts 10 and 11. 105

What I claim is:

1. A device of the character described, including a metallic tie plate adapted to rest upon a railway tie, and receive the rail, said plate being provided with spike holes 110

- on opposite sides, said plate being reinforced on opposite sides of said holes, ribs integral with and upstanding from said plate, whose inner ends abut against the spikes driven through said holes, a catch carried by the inner sides of said plate and engaging over the flange of the rail, a cam shaped anchor having a serrated periphery carried by the outer side of the plate, and engaging against the outer flange of the rail to prevent the lengthwise movement of the rail relative to the plate, and a yieldable member adapted to hold said anchor in contact with the rail.
- 15 2. A device of the character described, including a tie plate adapted to rest upon a railway tie and receive the rail, said plate being provided with spike holes on opposite sides and being reinforced on opposite sides

of said holes, ribs integral with and upstanding from said plate, whose inner ends abut against the spikes driven through said holes, a catch carried by the inner sides of said plate and engaging over the flange of the rail, a cam shaped anchor having a serrated periphery carried by the outer side of the plate, and engaging against the outer flange of the rail to prevent the lengthwise movement of the rail relative to the plate, and a yieldable member adapted to hold said anchor in contact with the rail.

In testimony whereof I have signed my name to this specification in the presence of two subscribing witnesses.

ROBERT JOHNSON.
